CLAIM

The ornamental design for a shoe upper, as shown and described.

DESCRIPTION

FIG. 1 is a first side view of a shoe upper showing my design according to a first embodiment;

FIG. 2 is a first side perspective view thereof; and,
FIG. 3 is a top view thereof.

The long-and-short broken lines form an unclaimed boundary around at least a portion of the claimed subject matter, and form no part of the claim. The even-length broken lines, which show the remainder of the article, are directed to environment, represent unclaimed subject matter, and form no part of the claimed design.

The difference in stipple shading in the claimed portion represents a contrast in appearance.
